UNITED STATES PATENT OFFICE.

BLANCHE M. BURNETT, OF HIGHLAND PARK, MICHIGAN.

DESIGN FOR A BOOK END.

Application filed April 7, 1923. Serial No. 5,720. Term of patent 3½ years.

To all whom it may concern:

Be it known that I, BLANCHE M. BURNETT, a citizen of the United States, residing at Highland Park, in the county of Wayne and State of Michigan, have invented a new, original, and ornamental Design for Book Ends, of which the following is a specification, reference being had to the accompanying drawing, forming a part thereof.

Fig. 1 is a front elevation and Fig. 2 a side elevation of a book-end embodying my design.

I claim:—

The ornamental design for a book-end as shown.

BLANCHE M. BURNETT.
